UNITED STATES PATENT OFFICE.

BARTON W. SCOTT, OF SAN JOSÉ, CALIFORNIA, ASSIGNOR TO THE GLOBE DEVELOPEMENT COMPANY, OF SAME PLACE.

COIN-CONTROLLED VENDING APPARATUS.

SPECIFICATION forming part of Letters Patent No. 633,966, dated September 26, 1899.

Application filed March 20, 1899. Serial No. 709,771. (No model.)

To all whom it may concern:

Be it known that I, BARTON W. SCOTT, a citizen of the United States of America, residing in the city of San José, in the county of Santa Clara and State of California, have invented new and useful Improvements in Coin-Controlled Vending Apparatus, of which the following is a specification.

This invention has for its object, mainly, the production of a machine or apparatus for vending or distributing books and packages, the operation of which is controlled by the introduction of a coin of given value into the mechanism; and the invention comprises certain novel parts and combination of parts and mechanism producing an improved machine or apparatus of the character named, as hereinafter fully described, and set forth in the claims at the end of this specification.

The accompanying drawings referred to therein and forming a part thereof represent a machine embodying the said improvements.

Figure 1 is a front elevation having a portion of the case broken away to expose the parts inside. Fig. 2 is an end elevation taken from the right-hand side of Fig. 1 with the case partly in section. Fig. 3 is a front view in detail, on an enlarged scale, of the bottom frame of the racks, the traveling scraper, and the endless chain and sprocket-wheels that operate the scraper, the parts being broken away and contracted for the purpose of bringing the figure within the limits of the sheet. Fig. 4 is a front view in detail, on an enlarged scale, of the bottom part of the racks and the traveling scraper. Fig. 5 is a front view of the coin-controlled operating mechanism. Fig. 6 is a side view taken from the right-hand side of Fig. 5. Fig. 7 is a sectional view taken in a vertical plane xy , Fig. 6. Fig. 8 is a plan or top view of the stationary frame and inclined bottom plates beneath the book-holding racks shown in Fig. 4 with the racks removed.

The principal parts or features of this apparatus include several racks or frames within an inclosing case, each adapted to hold a number of small books in a tier or pile, a traveling scraper or device movable in a substantially horizontal path beneath and at right angles to the pile and by that movement caused to engage and draw the lowermost

book sidewise from beneath the pile, and means for moving said device along under the several piles, so as to remove the books from one pile after another in regular successive order from time to time as the apparatus is operated.

Another novel part or feature consists in mechanism of novel construction for actuating the scraper or discharging device and a coin-controlled means for throwing the same into and out of operative condition to withdraw a book from one of the piles as often as a coin is deposited in the receptacle provided for it in the case.

A machine or apparatus of any desired capacity is produced by increasing or reducing the number and the height of the racks shown in the drawings and by giving the traveling scraper the required length of movement to pass under and act upon all the piles in succession. These parts are combined and arranged for operation in an inclosing case provided with an opening for discharging the books from each pile to the outside and with a coin-slit and a conductor to carry the deposited coin into the scraper-operating mechanism and a lever for operating the scraper from the outside of the case.

Small packages, articles, or substances of a flat shape capable of being laid one upon another in an even pile can be vended or distributed from this apparatus simply by constructing the racks of proper size to contain the articles or packages in which they may be put up and giving the scraping device the required length of throw.

A indicates the case inclosing the racks and vending mechanism.

B is a horizontally-set frame below the racks, having ways or guide-slots b for two endless chains or link-belts C C.

D D' are two pairs of sprocket-wheels on parallel axles d d' at opposite ends of the frame, around which the endless belts are laid and carried.

The part herein termed the "scraper" is composed of a flat blade or bar E, loosely attached by arms E' E'' to the link-belts C C at one of the joints e , on which points it is free to play up and down as it is drawn along over the inclined bottom plates G. By virtue of its weight and being loosely pivoted

at e the scraper resting on the bottom plates travels in contact with them as it is moved by the belt, and being of proper length also to extend from side to side of the stationary frame between the side bars B B , so that it will run on the inclines g^x at the ends of the opening between one plate G and the next, the scraper runs down the surface of one plate and then up the incline onto the next plate, sufficient clearance being provided between the inclined plates and the bottom bar H^x of the rack for the turned-up edge of the scraper to clear the bottom of the racks. The forward or leading edge of the scraper is turned up at right angles, or nearly so, as shown in Figs. 4 and 8, to strike the hook or package squarely and carry it forward. Across this opening several slats or flat strips G , corresponding in number to the tiers or piles of books in the machine, are fixed between the sides of the frame at intervals apart, so as to leave between one plate and the next a slit or aperture equal at least in length and width to the length and thickness of the book.

Over each bottom slat a rack composed of a top frame H and a bottom frame H^x , united by upright bars or wires h h , supports the books in an even pile with the bottom book resting on the slat, and the slats have a slight dip or inclination transversely of the length and all in the same direction under the racks, the inclination from the horizontal in each slat being sufficient to give an opening of ample length and width between the lower edge of one slat and the higher edge of the next slat for the book to pass out when drawn or pressed sidewise, as before described.

The traveling scraper, moving from end to end of the frame upon the top face of the bottom slats and under the racks, operates by contact with the edge of the lowermost book in each pile to carry along and discharge the book from the bottom of the pile.

In the present construction of the apparatus the scraper discharges one book each time the operating-handle of the machine is moved, and the intervals of rest between the movements of the scraper or when it is set in motion by the handle are so regulated and determined by a coin-controlled device that only one book can be discharged and obtained from the machine at each operation, and it is necessary to deposit a coin as often as a book is to be withdrawn from the machine.

The means employed to operate the scraper consist of the endless link-belts C C , running over two sets of sprocket-wheels D D' , as before described, to which the scraper is attached, and a hand-lever I outside the case, connected with the shaft d^2 of the carriers D and composed, as shown in Figs. 5, 6, and 7, of a disk L , fast on the axle d , and a second disk M , rotatable independently of the disk L and secured to a short shaft or axle d^2 , that extends through the case to the outside and is provided with the hand-lever I . The two

disks L M being normally disconnected from each other, the sprocket-wheels cannot be operated except when the two disks are locked together or caused to engage each other, and no movement of the scraper takes place until the coin that actuates or sets in play the locking device between the two disks is deposited in the machine. This locking means is composed of hinged dogs N , pivoted at N' to the front or inner face of the disk L , and a stop-bar P on the outer face of the other disk, standing radially outward beyond the circumference of that disk and overhanging the rim of the adjacent disk L , this part P being of such shape and occupying a proper working position with relation to the edge of the disk L that the pivoted dogs N will pass under and clear the projection P so long as the dogs lie in a closed position within the rim of the disk, and on the other hand the outward throw of any one of the dogs will cause its end to strike the stop P , and thereby lock one disk to the other when the front disk is turned in the direction of the arrow x . In the inner face of the front disk is a recess S with a concentric bottom edge and a pocket S' at the end running toward the axis in the inner face of the disk of proper depth and width to admit a coin of the required size or denomination and to hold it in such position when inserted flatwise that its upper edge or rim will engage and throw out the pivoted dog with which it is brought in contact when the disk is turned. When this takes place, the two disks will turn together as the lever-arm I is moved, and the link-belts will be drawn along through their stationary guides a greater or less distance, according to the length of stroke given to the hand-lever. The movement is governed by the two stops T T' , between which the lever is free to move on its center, and in the present construction the length of stroke is sufficient to move the scraper across the top of one inclined bottom plate by one stroke of the lever. A spiral spring V , attached to the hub of the disk M and to a fixed point on the case, throws the lever upward against the top stop T and brings the disk back to position when the hand is removed from lever.

By such return movement of the disk M the coin is carried under the dog at that time resting upon it and is caused to roll on the concentric edge of the recess and drops into deeper part of the pocket S' at the end, whence it falls into a receptacle provided in the case. A stationary coin-chute W^x , leading from the coin-slit W^2 in the case W to the recess S between the two disks, conducts the coin into place and into operative position between the stop P and the nearest dog lying in front of the stop.

In the present construction the length of movement required in the scraping device E is equal to one-sixth the circumference of the sprockets, and the locking-disk on the sprocket-wheel-shaft is provided with six locking-dogs, so that there is always one dog left

in proper position in front of or on the operating side of the stop P when the lever-arm returns to place after being released, while the other disk has but a single stop P, because its movement is an oscillating one agreeing in extent with the movement of the hand-lever.

An inclined chute W³ beneath the racks and extending from the rear side forwardly to an opening W in the front of the case receives and discharges the books to the outside as often as they drop through the openings in the inclined slats.

Having thus fully described my invention, what I claim as new, and desire to secure by Letters Patent, is—

1. A coin-controlled vending and distributing apparatus for books and packages, including a plurality of book-holding racks at intervals apart in a row, stationary guide-frame beneath said racks, laterally-inclined rack-bottoms separated from one another by outlet-slits, endless traveling belts adapted to travel in the same direction through the frame, a scraping device attached to and carried by the belts so as to pass over one inclined bottom after another in succession, and coin-controlled means for imparting intermittently-progressive movement of the scraping device over the whole set of inclined bottoms to discharge a book from the series of piles in regular successive order, consisting of sprocket-wheels, a rotatable disk fast on the axle of the sprocket-wheels, a loose rotatable disk in close relation to the first-mentioned disk, a handle for rotating the last-named disk, and means acted on by a coin introduced between said disks to lock the same together and thereby give motion to one disk by the movement imparted to the other disk.

2. In a coin-controlled vending apparatus the combination, with a rack having a laterally-inclined bottom adapted to support the contents of the rack in a pile and a discharge-aperture along the lower edge of the said bottom; of a traveling scraper movable in the same direction over the inclined bottom and adapted to engage and discharge from the said bottom through the aperture the lower-most article in the pile, and coin-controlled means for moving the scraper intermittently in the same direction, comprising the link-belts to which the scraper is attached, sprocket-wheels, a rotatable disk fast on the axle of the sprocket-wheels, a loose disk having an operating-handle, and coin-controlled means locking said disks together by the insertion of a coin, substantially as described.

3. The combination of the rotatable disk fast on a shaft to be rotated, dogs on the face of the disk normally held within the circumference of the rim but movable outward beyond the rim, a second disk mounted for rotative movement on a separate axle, and carrying a stop projecting over the rim of the first-mentioned disk and the path by the dogs thereon and adapted to lock one disk to the other by the outward movement of a dog, one of said disks having a recess for inserting a coin between the disks, said recess by its shape and location being adapted to bring the inserted coin into engagement with a dog, and means for giving rotative movement to the coin-receiving disk, for operation as described.

In testimony that I claim the foregoing I have hereunto set my hand and seal.
